UNITED STATES PATENT OFFICE.

JONATHAN W. HARRIS, OF MONTCLAIR, NEW JERSEY, ASSIGNOR TO WESTERN ELECTRIC COMPANY, INCORPORATED, OF NEW YORK, N. Y., A CORPORATION OF NEW YORK.

TELEPHONE-TRANSMITTER MOUTHPIECE.

1,334,093.

Specification of Letters Patent. Patented Mar. 16, 1920.

Application filed October 18, 1916. Serial No. 126,236.

To all whom it may concern:

Be it known that I, JONATHAN W. HARRIS, a citizen of the United States, residing at Montclair, in the county of Essex and 5 State of New Jersey, have invented certain new and useful Improvements in Telephone-Transmitter Mouthpieces, of which the following is a full, clear, concise, and exact description.

10 This invention relates to telephone mouthpieces and the method of making them, and has for its object a mouthpiece which may be readily cleaned and one more durable and more easily manufactured than those 15 commonly in use at the present time.

The telephone mouthpieces of hard rubber or rubber-like compounds, which have heretofore been in common use, are objectionable because they soften and lose shape when 20 placed in hot water to be cleaned, and also because they are easily broken or chipped in service. Those made of porcelain or similar substances, which screw directly into the face-plate of the telephone transmitter, or 25 into an adapter which is itself screwed or otherwise fastened to the transmitter face, have failed to meet commercial requirements satisfactorily because the threads are difficult to produce with accuracy and are easily 30 chipped, the broken particles therefrom often interfering with the operation of the transmitter. Mouthpieces wherein the porcelain or similar portion is held to the transmitter face-plate by a screw-threaded metal 35 ferrule or adapter to which the porcelain is cemented, have been found to be unsatisfactory because of the difficulty of procuring a cement which will not dissolve or lose its properties in boiling water, and because the 40 cements have been found to harden to such an extent that the structure is substantially rigid, resulting in a high percentage of chipped and broken mouthpieces under usual service conditions.

45 It is to eliminate all of the above objections that this invention contemplates a telephone mouthpiece wherein the porcelain or similar portion is secured to the adapter or ferrule by a resilient adhesive binder which 50 is insoluble in water at ordinary boiling temperatures. More specifically, the invention contemplates a mouthpiece wherein a porcelain or similar body-portion is secured to a metal adapter or ferrule by vulcanized rub-

ber and to a process for producing such a structure.

The invention will be fully understood from the following description taken in connection with the accompanying drawing wherein the preferred construction is illustrated, Figure 1 showing the assembled structure partly in section; Figs. 2, 3 and 4 illustrating various details of the structure of Fig. 1; and Fig. 5 showing an alternative structural arrangement.

A body-portion 5 of the usual funnel shape, and preferably of porcelain, is provided at its base with a contracted portion 6. This contracted portion is provided with a roughened surface which may be formed in the shape of a partial screw-thread 7, as clearly shown in Fig. 2. The adapter or ferrule 9 comprises a metal ring having an enlarged portion 10 and a contracted portion 11, as most clearly indicated in Figs. 1 and 4. The contracted portion is outwardly threaded to engage the threads in the face-plate of a telephone transmitter (not shown). The enlarged portion 10 is roughened on its inner surface in any desired manner to increase the adhesion between such surface and the binder 12.

The binder 12, which secures the body-portion 5 and the adapter 9 together, is preferably applied in the form of a band or strip 85 of rubber compound which, in assembling the structure, is wrapped around the contracted portion 6 of the porcelain. It has been found that very satisfactory results are obtained by using rubber compound 90 sheeting about $\frac{1}{16}$ of an inch in thickness, which is cut into strips of approximately $\frac{1}{4}$ of an inch wide and about $3\frac{1}{2}$ inches long. This strip is wrapped around the constricted and threaded portion of the porcelain, and 95 the ferrule 9 is then pressed into place and held by a suitable clamp. The assembled structure is then placed in an oven and kept at a temperature of approximately 170° centigrade for one or two hours to vulcanize the 100 rubber. This process forms a resilient adhesive binder securely fastening the porcelain and ferrule together. The structure is very easily assembled, and may be cleansed in boiling water without any resulting damage. The resiliency of the rubber after vulcanization is sufficient to enable it to absorb 105 shocks resulting from very rough usage of

the mouthpiece with a minimum danger of breakage.

In the alternative structure illustrated in Fig. 5, the body-portion 5 of the mouthpiece is fastened by the resilient binder 12 to an intermediate ring or ferrule 13, which in turn is threaded into the ferrule 9.

This is an arrangement which under some circumstances may prove desirable for manufacturing reasons, or as a means for improving the appearance of the mouthpiece.

What is claimed is:

1. The method of securing a ferrule to the body portion of a telephone transmitter mouthpiece which consists of inserting a resilient shock absorbing member of vulcanizable material therebetween and subjecting the combined structure to a vulcanizing temperature.
2. The process of making telephone transmitter mouthpieces which consists of interposing a resilient shock absorbing member of vulcanizable material between the body por-

tion and the attaching member and subjecting the combined structure to a vulcanizing temperature until the resilient member adhesively secures the attaching member to the body portion.

3. The method of securing the ferrule to the body portion of a telephone transmitter mouthpiece which consists of inserting a layer of rubber compound therebetween and subjecting the compound to a vulcanizing temperature.

4. The method of securing an attaching member to the body portion of a telephone transmitter mouthpiece which consists of inserting a member of vulcanizable material therebetween and subjecting the material to a temperature of approximately 170° centigrade for a period of from one to two hours.

In witness whereof, I hereunto subscribe my name this 17th day of October, A. D., 1916.

JONATHAN W. HARRIS.
